No. 631,348.

Patented Aug. 22, 1899.

A. M. WAITT & H. F. BALL.
JOURNAL BOX FOR RAILWAY CARS.

(Application filed Apr. 6, 1899.)

(No Model.)

UNITED STATES PATENT OFFICE.

ARTHUR M. WAITT AND HERMAN F. BALL, OF CLEVELAND, OHIO.

JOURNAL-BOX FOR RAILWAY-CARS.

SPECIFICATION forming part of Letters Patent No. 631,348, dated August 22, 1899.

Application filed April 6, 1899. Serial No. 712,012. (No model.)

To all whom it may concern:

Be it known that we, ARTHUR M. WAITT and HERMAN F. BALL, residing at Cleveland, in the county of Cuyahoga and State of Ohio, 5 have invented certain new and useful Improvements in Journal-Boxes for Railway-Cars; and we do hereby declare the following to be a full, clear, and exact description of the invention, such as will enable others skilled 10 in the art to which it pertains to make and use the same.

Our invention relates to improvements in journal-boxes for railway-cars, and more especially to a box of the character indicated 15 that is provided at its outer end with a lid that is adapted to close the said end and is hinged to the box proper at the latter's top.

The primary object of the invention is to provide a construction that will exclude the 20 ingress of dust into the outer end of the box at the top, bottom, and sides of the box between the lid and the box proper.

With this object in view and to the end of rendering the construction simple, durable, 25 and convenient the invention consists in certain peculiarities of construction and combinations of parts hereinafter described, and pointed out in the claims.

In the accompanying drawings, Figure I is 30 an outer end elevation of a journal-box embodying our invention. Fig. II is a section on line II II, Fig. I, looking outwardly. Fig. III is a section on line III III, Fig. I, looking outwardly. Fig. IV is a central vertical section 35 of the outer end portion of the box. Fig. V is a section on either one of lines V V, Fig. II, looking in the direction of the arrow. Fig. VI is a top plan of the outer end of the box.

Referring to the drawings, *a* designates the outer end portion of the box proper of our 40 improved journal-box. The box proper is open at its outer end in the usual manner for affording access to the box, and the said end is closed by a lid *b*, that is hinged or pivoted 45 horizontally and transversely of the box to the top of the outer end of the box proper. The outer end of the box proper is provided at the top with an upwardly-projecting lug 50 *a'*, that is integral with the box proper and is arranged centrally of the pivotal connection

between the lid and the box proper. The said pivotal connection comprises two sleeves or ears *b' b'*, that are formed upon the lid at opposite sides, respectively, of the lug *a'* and 55 embrace the pivotal pin *c* of the pivotal connection, which pin extends, therefore, horizontally and easily through members *b'* of the lid and extends through a hole *a''* formed in the lug *a'* of the box proper. The upper portion 60 of the lid is enlarged forwardly, as at *b''*, to accommodate the location and operation of the spring *d* employed to retain the lid in the latter's closed position. The said spring is interposed between the inner side 65 of the lid and the forward side of the lug *a'* and extends from a point forwardly of the said lug, against which it bears, downwardly and is secured at its lower end to the lid in any approved manner. The forwardly enlarged portion *b''* of the lid has the shape required to form a hood that covers the lug *a'* at the front, sides, and top and prevents 70 dust and dirt from entering the space behind the lid around the lug *a'*. To prevent dust 75 and dirt from entering the space within portion *b''* of the lid at the top and rear of the lug *a'*, the said lug is provided with a rearwardly-facing shoulder *a''*, that is formed upon the lug in any approved manner, which 80 shoulder extends the full width of the lug and is engaged by a flange *b''*, that is formed upon and depends from the upper end of the hood-forming portion *b''* of the lid and snugly engages the aforesaid shoulder in the lid's 85 closed position. The lug's portion *a''* below the shoulder *a''* has a trend concentric of the axis of the pivotal connection between the lid and the box proper, so as not to obstruct the sweep of the flange *b''* when the lid is 90 swung from its closed to an open position, or vice versa.

To prevent the ingress of dust and dirt into the forward end of the box proper, at opposite sides of the lug *a'*, the lid *b*, below and a 95 short distance from the sleeves *b'*, is provided with rearwardly-projecting flanges *b''*, that are arranged concentrically of the axis of the pivotal connection between the lid and the box proper and closely overlap the shoulders 100 *a''* upon the box proper, which shoulders extend also concentrically of the axis of the said

pivotal connection. The trend of the shoulders a^5 and the overlapping flanges b^5 , concentrically of the axis of the aforesaid pivotal connection, accommodates the swinging of the lid, as required in actuating the lid from a closed to an open position, or vice versa. We would here remark that the lid b has bearing upon the box proper preferably only at shoulders a^5 , as in the case illustrated, and not at the pivotal pin, and to insure an adequate bearing between flanges b^5 and shoulders a^5 at all times the pin-hole a^2 in lug a' is elongated downwardly and in line with the lid when the latter is in its closed position, so as to accommodate the descent of the lid, and consequently the lid's flanges b^5 , as required, to take up any wear upon or between the bearing forming surfaces of flanges b^5 and shoulders a^5 , and hence a tight joint is always maintained between the said members a^5 and b^5 in the closed position of the lid.

To prevent the ingress of dust and dirt into the outer end of the box proper from below, the lid is provided at its lower end with a rearwardly and downwardly projecting flange b^4 , that in the closed position of the lid overlaps the outer side of the bottom of the box proper.

To exclude dust and dirt from entering the outer end of the box proper at the latter's sides, the lid is provided at each side with a rearwardly or inwardly projecting flange b^6 , that extends from top to bottom of the lid and is arranged to engage in the closed position of the lid a groove a^6 , formed in the adjacent side of the box proper, which groove extends from top to bottom of the box.

As shown in dotted lines, Fig. I, the flanges b^5 b^5 extend from lug a' to and terminate in the different flanges b^6 b^6 , respectively. Flanges b^6 extend from flanges b^5 to and terminate in flange b^4 , and flange b^4 extends, therefore, from the flange b^6 at one side of the box to the flange b^6 at the opposite side of the box. In fact flanges b^4 , b^5 , and b^6 form a continuous flange that extends from one side of lug a' to the other side of the said lug. The grooves a^6 are open at their ends, as already indicated, and the two open ends of each groove a^6 are arranged, preferably, in a straight line, so that a stick capable of entering the said groove endwise can be conveniently used in cleaning the groove. We would remark also that preferably the bottom of the box is provided externally with a forwardly-facing shoulder a^7 , extending from side to side of the box and arranged to overlap the longitudinal edge of flange b^4 in the closed position of the lid. The said shoulder a^7 is instrumental in preventing air-currents from carrying or forcing dust or dirt in between the inner side of the said flange and the bottom of the box in the lid's closed position.

What we claim is—

1. In a journal-box of the character indicated, the combination with the box proper that is open at its outer end and has a lug

projecting upwardly from the forward extremity of the said end: of the lid for closing the said end; the pivotal connection between the said lid and the aforesaid lug, which pivotal connection has a pivotal pin extending horizontally through the lug, and a flange formed upon and depending from the upper end of the lid rearwardly of the aforesaid lug and extending the full width or approximately the full width of the lug, which flange has the arrangement required to cause it to snugly engage the lug in the closed position of the lid, substantially as and for the purpose specified. 80

2. In a journal-box of the character indicated, the combination with the box proper that is open at its outer end and is provided, at the central portion of the top of the said end, with an upwardly-projecting lug; of the lid for closing the aforesaid end of the box proper, which lid is pivoted horizontally to the aforesaid lug and has two rearwardly-projecting flanges at opposite sides, respectively, of the said lug, which flanges have the arrangement required to cause them to snugly overlap the top of the box proper in the lid's closed position, substantially as and for the purpose specified. 90

3. In a journal-box of the character indicated, the combination with the box proper that is open at its outer end and has a lug projecting upwardly from the upper extremity of the central portion of the said end, which lug, at the top, has a rearwardly-facing shoulder extending the full width of the lug: of the lid for closing the aforesaid end of the box proper, which lid has the shape required to cover the forward portion of the aforesaid lug; the pivotal connection between the lug and the lid's upper end, which pivotal connection comprises a horizontally-arranged pin extending through the lug, and two sleeves or ears formed upon the lid at opposite sides, respectively, of the lug, and embracing the pin; a flange depending from the upper end of the lid rearwardly of the aforesaid shoulder and having the arrangement required to snugly engage the shoulder in the lid's closed position, and two rearwardly-projecting flanges formed upon the lid a suitable distance below the pivotal pin, and at opposite sides, respectively, of the aforesaid lug, which last-mentioned flanges have the arrangement required to snugly overlap the box proper in the lid's closed position, substantially as and for the purpose specified. 100

4. A journal-box of the character indicated, comprising a box proper that is open at its outer end and has a lug projecting upwardly from the central portion of the top of the said end; a lid for closing the said end; a pivotal connection between the lid's upper end and the aforesaid lug, and comprising a pin extending through the lug, and two ears formed upon the lid at opposite sides, respectively, of the lug and embracing the pin; two shoulders formed upon the box proper at opposite sides, respectively, of the aforesaid lug; flanges

formed upon the lid and arranged to closely overlap the said shoulders in the lid's closed position, and the pin-engaging hole in the lug being elongated in the direction of the lid's 5 free end when the lid is in its closed position, substantially as and for the purpose set forth.

5. A journal-box of the character indicated, comprising a box proper that is open at its outer end and has a lug projecting upwardly 10 from the central portion of the top of the said end; a lid for closing the said end; a pivotal connection between the lid's upper end and the aforesaid lug, and comprising a pin extending through the lug, and two ears formed 15 upon the lid at opposite sides, respectively, of the lug and embracing the pin; two shoulders formed upon the box proper at opposite sides, respectively, of the aforesaid lug, which shoulders are arranged concentrically 20 of the axis of the pivotal connection; flanges formed upon the lid and arranged to closely overlap the said shoulders in the lid's closed position, and the pin-engaging hole in the lug being elongated in the direction of the lid's 25 free end when the lid is in its closed position, substantially as and for the purpose set forth.

6. In a journal-box of the character indicated, the combination with the box proper that is open at its outer end and provided, at 30 the top of the said end, with the shoulders a^5 , a^5 and the lug a' that has the rearwardly-facing shoulder a^3 and the horizontally-arranged pin-receiving hole a^2 elongated downwardly: of the lid b extending around the forward portion of the aforesaid lug and having the depending flange b^3 , the inwardly-projecting flanges b^5 b^5 ; the ears b' b' , and the pivotal pin c , all arranged and operating substantially as shown, for the purpose specified.

10. 7. In a journal-box of the character indicated, the combination with the box proper that is open at its outer end and provided with two grooves that are arranged at opposite sides, respectively, of the opening in the said 45 end and extend from top to bottom of the said end of the box proper; of the lid pivoted horizontally at its upper end to the box proper and provided with two inwardly-projecting flanges having such length and arrangement 50 relative to the aforesaid grooves that the flanges will engage the different grooves, respectively, in the lid's closed position and extend, respectively, from the upper end to the

lower end of the engaging groove, substantially as and for the purpose set forth.

55

8. In a journal-box of the character indicated, the combination with the box proper that is open at its outer end and provided with two forwardly-opening grooves that are arranged at opposite sides, respectively, of the 60 opening in the said end, and extend from top to bottom of the said end of the box proper; of the lid pivoted horizontally at its upper end to the box proper and provided with two inwardly-projecting flanges having such arrangement relative to the aforesaid grooves that the flanges will engage the different 65 grooves, respectively, in the lid's closed position and extend, respectively, from the upper portion to the lower portion of the engaging groove, which grooves are open at their upper and lower ends, substantially as and for the purpose set forth.

70

9. In a journal-box of the character indicated, the combination with the box proper 75 that is open at its outer end, and has the said end provided at the bottom and a suitable distance rearwardly of the forward or outer extremity of the said end with a forwardly-facing shoulder extending from side to side 80 of the box proper; of the lid for closing the said end of the box proper, which lid is pivoted horizontally to the top of the box proper, and has its free end provided with an inwardly-projecting flange that has the arrangement required to cause it to extend in 85 under the box proper in the lid's closed position and have its rear edge overlapped by the aforesaid shoulder.

10. In a journal-box of the character indicated, the combination with the box proper that is open at its outer end and provided with the shoulders a^5 a^5 and a^7 ; the grooves a^6 a^6 , and the lug a' that has the shoulder a^3 and the elongated pin-receiving hole a^2 , of the lid 95 b having the ears b' b' ; the flanges b^3 b^5 b^5 , b^4 , and b^6 b^6 , and the pivotal pin c , all arranged and operating substantially as shown, for the purpose specified.

Signed by us at Cleveland, Ohio, this 25th 100 day of March, 1899.
